REFRIGERATOR DOOR COVERING ATTACH-
MENT

Walter F. Davis and Carl E. Norelius, St. Paul,
Minn., assignors to Seeger Refrigerator Com-
pany, St. Paul, Minn., a corporation of Minne-
sota

Application December 6, 1930. Serial No. 500,602

9 Claims. (Cl. 20—35)

This invention relates to a refrigerator door covering attachment which is designed to hold the exterior door covering to the frame.

A feature of the door covering holding means 5 resides in a bracket member made of an angularly shaped member which is adapted to engage against the flange of a gasket such as is ordinarily used in the construction of refrigerator doors. The gasket flange provides a cushioning means 10 for the plate of the angle member which is attached to the door frame, while the bead of the gasket extends along the edge of the door covering and the wood frame to form a sealing means for providing the necessary seal about a door frame 15 and to form a cushion for the contacting edge of the door against the refrigerator body.

The door clip may be formed of an angular member or it may be in the form of a lug or bearing having the desired length to provide the 20 necessary strength for firmly supporting the door covering which is usually made of enamelled metal to the door frame proper which in some cases is made of wood. It is desirable to form refrigerator doors with an exterior enamelled 25 sheathing which may be termed the door pan or covering and also an inner sheathing or cover. Each of these members are made of metal and are enamelled to protect the surface of the same. The enamel of these pans may be of any character 30 and is usually of a color to match the rest of the refrigerator or the body which is covered with an enamelled sheathing. The interior of the door as well as the refrigerator is made of insulating material and in the door it is the frame and may 35 be made of any insulating material such as wood or other non-conducting substance which is not readily susceptible to heat or cold. In making the doors of the refrigerator it is desirable to have the outer sheathing covering or pan held along 40 the free edge of the door by clips such as we will more fully herein describe and set forth, while the other side of the door is held by the hinges. The outer door covering or pan is formed with an inturned edge and all of the surface of the door 45 covering including the inturned edge is enamelled.

It is desirable that the enamelled inturned edge of the door shall not come in contact with the enamelled surface of the refrigerator body. A gasket having a projecting bead or cushion is 50 ordinarily secured to the edge of the door frame and we provide a door clip either of an angular bar nature or in the form of a lug bar to engage beneath the inturned flange to hold the sheathing of the door in place. These clips may be 55 secured along the edge of the door frame.

Other details and features will be more fully and clearly set forth in the specification and claims.

In the drawing forming part of this specification:

Figure 1 illustrates a portion of a refrigerator with our door secured thereto, wherein the construction of holding means for the door covering is employed.

Figure 2 is a perspective detail partly in section, 65 showing the use and location of our door clip bar.

Figure 3 illustrates another form of the clip bar and is a sectional detail of a portion of a refrigerator door.

The drawing illustrates the refrigerator body 70 A which may be of any suitable form and construction designed to provide a refrigerating and food compartment such as B divided and fitted with supporting pans of any desired nature. The refrigerator A is formed with a door opening C 75 in which the door D is adapted to operate to open and close the refrigerator A.

The door D is supported by the hinges 10 on one side and is secured by the locking mechanism 11 on the other side.

In the door D the inner frame may be formed of wood or other insulating material and is provided with frame rails 12 which extend about to form the rectangular frame of the door and to which the inner rails 13 are secured to give the 85 desired thickness to the door frame. Suitable insulating material such as 14 may be placed in the center of the frame 12 to build up the door frame with the proper insulating structure. The inside of the wooden frame of the door D is adapted to be covered by the sheathing or pan 15 which is made of enamelled metal and which is secured to the door frame members in any suitable manner.

The outside of the door D is adapted to be 95 covered by the metal sheathing 16 which is enamelled in a similar manner to the sheathing 15. The sheathing 16 which covers the entire outer surface of the door insulating frame made up of the portions 12 and 13 and the insulation 14 is formed with an inturned peripheral flange 17 which extends around the ends 18 of the frame portions 12 and which is formed with an inwardly extending marginal flange 19 which extends virtually up to the edge 18 of the frame 105 members 12. The flanges 17 and 19 form the finishing edge of the outer covering 16 of the door D so as to extend the enamelled finish from the outer face around the edge of the door up to the members 12.

A gasket member E which is formed with a projecting bead or cushion 20 and an attaching flange 21 is secured around the edge of the door frame. This gasket has the bead member 20 positioned to bear against the surface of the rails 12 of the door frame and also cover and bear against the inner edge 22 of the flange 19. In this manner the gasket E forms a cushion between the frame rails 12 and the flange 19 of the outer covering 16 and also provides a gasket cushion for sealing the door D against the outer surface of the refrigerator A to make the door as nearly air-tight as possible and also to prevent the enamelled flange 19 of the door from striking the enamelled surface on the body of the refrigerator A.

We provide an angle iron clip F which is held by the screws 23 against the flange 21 of the gasket E and bearing against the edge 18 of the door frame. This clip F or clip bar is adapted to be of sufficient length to provide the necessary rigid engagement between the door frame and the covering 16 to hold the door covering or pan 16 firmly in place against the slamming of the door and virtually any use to which the door is subjected as a closure on the refrigerator A. One or more of these clips F may be used and it will be obvious that in larger doors more clips are required than on smaller doors and the length of the clip may be proportioned to the size of the door.

The clip F is formed with a flange 24 which extends under and engages the flanges 19. This flange 24 is of a narrow nature, and in fact, is preferably of a slightly less width than the width of the flange 19, or at least not greater than the inside width of the flange 19. The clip F is formed with a wider flange such as 25 through which the screws 23 extend and which bears against the flange 21 of the gasket E. The gasket forms a cushion for this flange and compensates for any inequalities in the engagement of the clip F with the flange 19.

The clip may be made in the bar form of wood, metal, bakelite or other suitable material, such as F', illustrated in Figure 3, and in this form it is a rectangular bar which is adapted to be held by the screws 26 extending into the edge of the member 12. This bar clip F' may be of any suitable length and operates in the same manner as the clip F.

With these clips, such as F, the outer door sheathing or covering 16 may be hooked upon the door frame made up of the rails 12 and 13 on the side of the door opposite the hinges 10. The covering is then brought over the other side of the door and by means of the screws of the door hinges 10, it is held firmly in place. Should it be desired to remove the door covering this may be quickly done by removing the screws which hold the door hinges to the door D. A deadening felt such as 27 is placed between the inner frame of the door D and the outer covering 16. This also provides an insulation between the door covering or pan 16 and the frame made up of the members 12 and 13 and also provides a desirable cushion. With our clip construction, door coverings or pans 16 may be easily attached or removed during inspection or in the construction of the refrigerator doors D and the nature of our clip provides a strong durable support secured to and projecting from the edge of the door frame to hold the covering of the free side of the door D firmly in place.

In accordance with the patent statutes we

have described the principles of our refrigerator door covering attachment and we have endeavored to represent the best embodiment thereof. The drawing is illustrative and the same may be carried out by other means and applied to other uses within the scope of the following claims.

We claim:

1. A refrigerator door covering attachment including, a clip member having an outwardly projecting flange, a door covering having an inwardly projecting flange under which said clip flange is adapted to engage, and a flange extending virtually at right angles to said clip flange adapted to provide an attaching means through which screws may extend to anchor said clip to the refrigerator door frame.

2. A refrigerator door covering attaching means in combination with an enamelled door covering, and an insulating inner door frame, a clip having a flat broad surface adapted to be attached to the edge of the insulating door frame, a narrow shoulder projecting from one edge of said clip, a marginal inturned flange formed on said door covering and spaced from the front thereof by a peripheral flange, said shoulder on said clip being adapted to engage under said marginal flange to support the door covering along one edge of the refrigerator door.

3. A refrigerator door including, an inner insulating door frame, an inner covering, an outer covering, a marginal inturned flange formed on said outer covering adapted to extend toward and in close proximity to said inner frame of said door, a gasket having its flange secured to the edge of said door frame and having the bead thereof extending between the inner door frame and the inner edge of said inturned marginal flange, and an outer door covering supporting clip having a bar-like formation extending along the edge over the flange of said gasket and secured thereto in a manner to form a shoulder to engage under said marginal flange of said door covering.

4. A refrigerator door including, an insulating door frame, a gasket having a flat flange and a bead projecting therefrom, the flange of said gasket being secured to the outer edge of said door frame, an outer covering for said door frame including an inwardly projecting marginal flange adapted to extend in close proximity to the bead of said gasket, and a bar-like supporting clip secured to the flange of said gasket and the edge of the door frame in position to provide a shoulder to engage under said marginal flange of said door covering to support the same along the edge of the refrigerator door frame.

5. A refrigerator door including, a door frame, an outer covering pan, an inwardly extending marginal flange formed on said pan, and an angular bar clip secured to the edge of said door frame and extending as a shoulder under said inturned flange.

6. A refrigerator door comprising, an inner insulating door frame of non-heat conducting material, a metal covering for the inner part of said door, an outer covering for said door frame, cushioning means between said door frame and said outer covering, a gasket around the edge of said door frame having a projecting bead, a marginal flange adapted to extend toward said bead, and a flange engaging clip secured to said door frame over said gasket to form a clip shoulder for holding said outer door covering to said door frame.

7. A refrigerator door including, an insulating frame, an outer covering sheet for said frame, a
